United States Patent Office.

LORENZO D. GILLETT, OF ROCHESTER, AND HENRY W. INMAN, OF DETROIT, MICHIGAN.

Letters Patent No. 83,150, dated October 20, 1868.

IMPROVED REIN-HOLDER.

The Schedule referred to in these Letters Patent and making part of the same.

To whom it may concern:

Be it known that we, LORENZO D. GILLETT, of Rochester, in the county of Oakland, and State of Michigan, and HENRY W. INMAN, of Detroit, in the county of Wayne, and State of Michigan, have invented a new and useful Improvement in Rein-Holders to be attached to wagons; and we do declare that the following is a true and accurate description thereof, reference being had to the accompanying drawings, and to the letters of reference marked thereon, and being a part of this specification.

The object of this invention is to construct an apparatus which will hold the reins of a team when not held by the driver, and is designed to be attached to the end of the dash or front of a wagon.

To accomplish this object, we cast in malleable iron, or in other suitable material, the bed-plate A, which should be concave upon the under side, in order to fit the rail of a leather dash, and provided with clips B, which, when the bed-plate A is in place, may be bent around said rail, thereby holding the apparatus rigidly in position. When used upon a wooden dash or wagon-front, the bed-plate may be provided with a suitable

flange, with suitable holes through the same, by means of which it may be, with proper screws, attached to the dash. This bed-plate should be also provided with a seat, C, to receive one end of the coil or other suitable spring, D, and also provided with ears E, to which to pivot the curved lever F.

Having attached the apparatus to the dash or wagon-front, as hereinbefore described, with the loose end of the curved lever pointing upward, the whole is ready to receive the reins, by simply passing the same between the upper end of said lever and the bed-plate, when the spring compels the lever to hold said reins in place, and allows them to be easily removed when desired.

What we claim as our invention, and desire to secure by Letters Patent, is—

The construction of a rein-holder, with bed-plate A, curved lever F, and spring D, arranged and operating substantially as herein described.

LORENZO D. GILLETT.
HENRY W. INMAN.
